FRANK T. CABLE, OF NEW LONDON, CONNECTICUT, ASSIGNOR TO ELECTRIC BOAT COMPANY, OF GROTON, CONNECTICUT, A CORPORATION OF NEW JERSEY.

REVERSIBLE INTERNAL-COMBUSTION ENGINE.

Application filed March 18, 1924. Serial No. 699,975.

This invention relates to four-cylinder internal combustion engines, and more particularly to a four-cylinder engine of the well-known Diesel type, which is different from 5 the ordinary four-cylinder Diesel engine in that it is reversible.

Reversible Diesel engines having more than four-cylinders are now in common use, but heretofore it has not been considered 10 possible to make a satisfactory four-cylinder reversible internal combustion engine of this type, due to the fact that two of the engine pistons are connected to cranks spaced 180° apart from the remaining 15 cranks of the crank shaft, and consequently the crank shaft occasionally stops on dead center. Accordingly four-cylinder Diesel engines cannot be used for many purposes unless reversing gears are provided, so as to 20 permit the engine to run in the same direction at all times.

The present invention was devised with a view to providing means whereby a four-cylinder Diesel engine can be stopped and 25 started in the reverse direction with very little effort and in a very short period of time. In general, my invention comprises means permanently associated with a four-cylinder engine whereby the crank shaft 30 can be turned away from its dead center position so that the engine can be started in either direction as determined by the position of the engine cam shafts, by admitting compressed air to the engine cylinders 35 in the usual manner. The invention includes means for moving the crank shaft away from its dead center position by a step by step movement which is used only in the event that the crank shaft stops within 10° 40 of this position, and additional means for quickly moving the crank shaft away from its dead center position when the shaft occupies a position at an angle of 10° or more away from its dead center position. 45 The invention also includes means for indicating at all times the position of the engine crank shaft.

This invention can be best understood by 50 considering the following detailed description which is to be taken in conjunction with the accompanying drawings, in which

Fig. 1 is a perspective view of a four-cylinder Diesel engine embodying my invention.

55 Figs. 2 and 3 are diagrammatic views,

partly in section, illustrating the operation of a part of my invention, and

Figs. 4 to 7, incl., are diagrammatic views of a crank shaft showing the manner in which my invention operates to turn the 60 crank shaft away from its dead center position.

The four-cylinder Diesel engine illustrated in Fig. 1 of the accompanying drawings comprises four vertical cylinders 1 surmounting a crank case 2 which rests upon the bed plate 3. The engine cylinders 1 are of ordinary construction and, accordingly, each is provided with an air intake valve 4 through which air from the engine room is drawn into the cylinders, a suitable slotted intake member 5 being provided on the exterior of each engine cylinder. A fuel valve 6 is provided at the top of each cylinder near the center thereof in accordance 70 with the usual practice. An exhaust valve 7 is provided for each cylinder, opposite the intake valve 4, the four exhaust valves communicating with an exhaust manifold 8. Each of the intake valves 4 is actuated 75 by a vertical lever 9 which carries a cam follower at the lower end thereof which cooperates with the cam shaft 10. In like manner, the exhaust valves 7 are connected to a cam shaft 11 by means of levers 12. Each of the fuel valves 6 is actuated by a lever 13 which in turn is actuated by a vertical lever 14 cooperating with the cam shaft 10.

A relief valve 4' is provided in each of 90 the engine cylinders 1, these valves being operated by means of a relief valve operating rod 5'.

A number of details have been purposely omitted from the drawings in order to avoid 95 complicating the drawings unnecessarily. It will be understood that a small starting valve is provided in the head of each of the four engine cylinders 1, these valves being in close proximity to the fuel valves 6. Furthermore, it will be understood that each of these air starting valves is actuated by a lever similar to the levers 13, and that a suitable starting lever is provided for the purpose of placing the starting valves in 100 condition to operate and permitting the fuel valves to remain closed during the starting period. Other details which have been purposely omitted from the drawings 105 include the ordinary pipe connections to the 110

fuel valves, the exhaust pipe leading away from the manifold 8, the air compressor, and the compressed air tanks.

The details which have been described above, with the exception of the cam shafts 10 and 11, are of ordinary standard construction and form a part of every four-cylinder Diesel engine. The following detailed description relates to the novel features I have provided in order to make the four-cylinder engine reversible.

The cam shafts 10 and 11 referred to above are provided with a double set of cams for causing the engine to operate in one direction or the other as determined by the operator. A hand lever 15 is provided for the purpose of shifting these cam shafts axially so as to bring either set of cams into position opposite the cam followers carried by the vertical levers 9 and 14. Suitable connecting linkages 16 are provided between the hand lever 15 and the cam shafts. The two cam shafts are driven through suitable gear connections (not shown) connecting these shafts to the engine crank shaft, one end of which is shown at 17. An indicator is provided for the purpose of showing the operator at all times the position of the engine crank shaft. This indicator, which may consist of a dial 18, pointer 19 and suitable mechanism for turning the pointer, can be geared to one of the cam shafts as shown at 20. The dial 18 may be specially marked, for example as indicated in Fig. 1, for the purpose of showing whether or not the engine crank shaft is within a predetermined angle, for instance 10° of its dead center position. When the form of indicator shown in Fig. 1 is employed, it is adjusted so that when the pointer 19 comes to rest over the shaded portion 21 of the dial, the engine crank shaft is within approximately 10° of its dead center position.

It will be appreciated that to provide a four-cylinder Diesel engine with reversing cam shafts such as the shafts 10 and 11, and with an engine crank shaft indicator such as that just described, would not be of great value, unless some means were provided for shifting or turning the engine crank shaft away from its dead center position far enough so that the engine can be started in either direction, as determined by the positions of the cam shafts, by admitting compressed air to the starting valves in the usual manner. Accordingly, I have provided two means for shifting the engine crank shaft, these means being permanently associated with the engine and cooperating to provide a thoroughly reliable system for rendering the four-cylinder engine reversible. In general, these two devices consist of a fluid pressure apparatus adapted to jack the engine crank shaft around, and means for supplying compressed air to two cylin-

ders of the engine, containing pistons connected to cranks disposed 180° apart.

The pipe 22 leads from the ordinary compressed air tanks (not shown) which are used in starting the engine. This pipe is connected to two cylinders of the engine by means of a main pipe connection 23 and short lateral connections 24 and 25. Suitable valves 26, 27 and 28 are provided for the purpose of regulating the flow of compressed air to these cylinders. This air connection can be made to any two of the engine cylinders containing pistons connected to cranks which are 180° apart.

The operation of the air connection system just described can be best understood by referring to Figs. 1 and 4 to 7 incl. If the valves 27 and 28 are open, the effect of opening the valve 26 in the air supply pipe 23 is to admit compressed air to two cylinders of the engine. This air will exert a force on the two pistons within these cylinders, which, it will be remembered, are connected to cranks 108° apart, and unless the engine crank shaft is within less than approximately 10° from its dead center position, the compressed air will expand and force the crank shaft away from its dead center position. For example, if the crank shaft 17 of Figs. 4 to 7 incl. is slightly off dead center, as shown in Fig. 6, and the compressed air exerts its force against pistons 29 and 30, the air will expand and force these pistons to move until they occupy the position shown in Fig. 7 or, in other words, until the crank shaft has been turned approximately 80°. The force exerted upon these pistons by the compressed air causes them to move until the combined volume of the spaces within the cylinders containing the compressed air, is a maximum, which of course is when the pistons occupy the position shown in Fig. 7.

It is, of course, true that where two pistons connected to cranks 180° apart are within say 10° of the dead center position, the free space in one of the cylinders is much greater than that in the other. Therefore, when compressed fluid, such as air, is admitted to these two cylinders, the pressure will build up faster in the cylinder having the smaller amount of free space above the piston than it will in the other cylinder. This will start the crank shaft rotating toward a position 90° away from the dead center position. But even if the pressure were the same in both cylinders, there would still be a strong tendency to rotate the crank shaft away from its dead center position. This can be demonstrated by simply resolving the two vertical forces on the pistons along the piston rods and then resolving the resultant forces at right angles to the cranks of the crank shaft.

If the engine crank shaft is on exactly

dead center, as shown in Fig. 5, or within approximately 10° of this position, the position of the crank shaft cannot be changed by merely admitting compressed air to two engine cylinders in the manner above described. In order to take care of this contingency I prefer to use means permanently associated with the engine for jacking the engine crank shaft around. In the embodiment of the invention illustrated in the accompanying drawings I have provided a ratchet wheel 31 fixed with respect to the engine crank shaft 17. This ratchet wheel can be fixed to the engine crank shaft directly, or to the engine fly wheel 32. The ratchet wheel 31 is adapted to be engaged by a pawl 33 carried by a yoke 34, which is rotatably mounted on the engine crank shaft. The pawl 33 is pivoted to the yoke near the closed end thereof, by means of a bolt 35. The outer or closed end of the yoke 34 is connected to a piston rod 36 in any suitable manner, for example by means of the bolt 37. The piston rod projects into a cylinder 38 which is pivoted on a stationary support 39 carried by the bed plate 3. The end of the cylinder 38 through which the piston rod 36 projects is closed by a cap 40 (see Fig. 2) which has a lug 41 thereon adapted to cooperate with a lug 42 carried by the pawl 33. These parts are arranged so that when the two lugs come together, the pawl is lifted from the ratchet wheel 31 and this wheel is free to rotate in either direction. The piston 43 connected to the piston rod 36 is moved back and forth within the cylinder 38 by admitting compressed air into one end of the cylinder and connecting the other end to atmosphere and then reversing this process. Accordingly, air connections in the form of pipes 44 and 45 are provided, extending between the cylinder 38 and the main compressed air supply pipe 22. The supply of compressed air to these connections 44 and 45 is controlled in the first instance by a valve 46 in the main supply pipe 22. In addition, a four-way valve 47 is provided at the point where the two supply pipes 44 and 45 are connected to the main supply pipe 22. This four-way valve or cock is provided with a handle or lever 48 by means of which the valve can be turned to connect the supply pipe 22 to either of the pipes 44 or 45, and simultaneously to connect the other of these pipes to the atmosphere through a suitable vent 49. With the hand lever in the position shown in Fig. 2, the compressed air from the pipe 22 is admitted to pipe 44 which conducts the air to the lower end of the cylinder 38. The other pipe 45 is connected to the atmosphere. The compressed air forces the piston 43 upward, the initial movement thereof causing the lugs 41 and 42 to become disengaged to allow the pawl 33 to drop into engage-

ment with the ratchet wheel 31, and the continued movement of the piston rod 36 turning the ratchet wheel 31, and consequently the engine crank shaft 17, until the piston 43 has reached the end of its travel, as shown in Fig. 3. If the hand lever 48 is then moved to the position shown in Fig. 3, the compressed air in the lower part of the cylinder 38 is discharged into the atmosphere through the vent 49 and the air supply pipe 22 is connected to the pipe 45 which conducts compressed air to the upper end of the cylinder 38. This forces the piston 43 to the lower end of the cylinder 38 and brings the yoke 34, and the pawl 33 carried thereby, back to their initial positions. By moving the hand lever 48 back and forth, from one extreme position to the other, the engine crank shaft can be jacked around to any desired extent, the position of the crank shaft being indicated at all times by the pointer 19.

I have found that it is seldom necessary to use the fluid pressure jacking device for turning the crank shaft, because it is seldom that the engine crank shaft comes to rest within approximately 10° of its dead center position. At all other times the crank shaft can be turned to a proper starting position by admitting compressed air to two cylinders in the manner described. When the engine crank shaft is substantially on dead center, the fluid pressure jacking apparatus can be employed for the purpose of moving the crank shaft far enough away from this position so that compressed air admitted to two engine cylinders will effect the necessary further movement of the crank shaft, or this further movement can be effected by continuing the jacking operation. In either event the time consumed in moving the engine crank shaft far enough away from its dead center position so that it can be started by admitting compressed air to the engine cylinders in the usual manner, requires only a few moments. In order to reverse the direction of rotation, it is only necessary to shift the cam shafts axially, when the engine is at rest. Then when the engine crank shaft has been turned away from its dead center position the proper amount, the engine can be started by introducing compressed air into the engine cylinders in the usual manner, that is by manipulating the lever which controls the operation of the air starting valves.

It is to be understood that the details of my invention can be modified without departing from the spirit of the invention which is not limited to the particular embodiments illustrated and described, but includes such modifications thereof as fall within the scope of the appended claims.

While my invention has been described as applied to a four-cylinder Diesel engine,

it may of course be used to advantage with four-cylinder engines of other types. It is particularly useful with Diesel engines for in this case it is not necessary to provide a special source of compressed air, the compressed air supply tanks used in starting the engine being suitable for supplying compressed air to two cylinders of the engine and to the jacking device in the manner above described.

10 I claim:

1. An internal combustion engine comprising at least two engine cylinders, pistons in said cylinders, a crank shaft having two cranks spaced 180° apart, means for connecting the cranks to the pistons, means for reversing said engine including a reversing shaft, fluid starting means for said engine, means for forcing the crank shaft away from a position near its dead center position including fluid pressure connections for simultaneously admitting compressed fluid to the two cylinders of the engine having the pistons connected to the cranks spaced 180° apart, whereby said pistons are brought into substantially the same horizontal plane and the engine adapted to be started in either direction.
2. An internal combustion engine comprising four engine cylinders, pistons in said cylinders, a crank shaft, two of the cranks of said crank shaft being spaced 180° apart, means for connecting the cranks to the pistons, means for reversing said engine including a reversing shaft, fluid starting means for said engine, means for forcing the crank shaft away from a position near its dead center position including fluid pressure connections for simultaneously admitting compressed fluid to the two cylinders of the engine having the pistons connected to the cranks spaced 180° apart, and a valve for admitting compressed fluid to said connections simultaneously, whereby said pistons may be brought into substantially the same horizontal plane and the engine adapted to be started in either direction.
3. An internal combustion engine comprising four engine cylinders, pistons in said cylinders, a crank shaft, two of the cranks of said crank shaft being spaced 180° apart, means for connecting the cranks to the pistons, means for reversing said engine including a reversing shaft, fluid starting means for said engine, means for jacking the engine crank shaft around when it is on

substantially dead center whereby the crank shaft can be turned through a small angle away from its dead center position, a source of compressed fluid, pipe connections from said source of compressed fluid to the two engine cylinders containing the pistons connected to the cranks spaced 180° apart, and a manually operable valve for admitting compressed fluid to said two cylinders through said pipe connection whereby the crank shaft can be moved further away from its dead center position, the pistons brought into substantially the same horizontal plane and the engine started in either direction.

4. An internal combustion engine comprising four engine cylinders, pistons in said cylinders, a crank shaft, two of the cranks of said crank shaft being spaced 180° apart, means for connecting the cranks to the pistons, means for reversing said engine including a reversing shaft, fluid starting means for said engine, means for jacking the engine crank shaft around when it is on substantially dead center whereby the crank shaft can be turned through a small angle away from its dead center position, means for admitting compressed fluid to the two cylinders of the engine having the pistons connected to the cranks which are spaced 180° apart to force the crank shaft further from its dead center position, and bring the pistons in said cylinders into substantially the same horizontal plane so that the engine may be started in either direction, and means for indicating the position of the engine crank shaft.

5. An internal combustion engine comprising four engine cylinders, a crank shaft, two of the cranks of said crank shaft being spaced 180° apart, means for connecting the cranks to the pistons, means for reversing said engine including a reversing shaft, fluid starting means for said engine, fluid pressure connections to the two cylinders of the engine having the pistons connected to the cranks which are spaced 180° apart, and a valve for admitting compressed fluid to these connections whereby the crank shaft can be moved away from its dead center position and the pistons connected to the cranks spaced 180° apart brought into substantially the same horizontal plane and the engine started in either direction.

In testimony whereof I affix my signature.

FRANK T. CABLE.
